2 SHEETS—SHEET 2.

UNITED STATES PATENT OFFICE.

MARY R. KEEGAN, OF WOODSFIELD, OHIO.

COLLAPSIBLE WARDROBE.

1,385,555.

Specification of Letters Patent. Patented July 26, 1921.

Application filed August 16, 1920. Serial No. 403,901.

To all whom it may concern:

Be it known that I, MARY R. KEEGAN, a citizen of the United States, residing at Woodsfield, in the county of Monroe and

5 State of Ohio, have invented certain new and useful Improvements in Collapsible Wardrobes, of which the following is a specification, reference being had to the accompanying drawings.

10 This invention relates to collapsible or foldable furniture, and particularly to a collapsible or foldable wardrobe structure.

15 The general object of the invention is to provide a garment supporting structure adapted to be unfolded and to be covered with a drapery.

20 A further object is to provide a structure of this character including crossed folding legs, and top braces holding the legs spread apart and a hanger supported from the top.

My invention is illustrated in the accompanying drawings, wherein:—

25 Figure 1 is a perspective view of a collapsible wardrobe constructed in accordance with my invention;

Fig. 2 is a perspective view of the framework of the wardrobe;

30 Fig. 3 is a fragmentary longitudinal vertical sectional view of one end of the frame and the covering;

Fig. 4 is a detail perspective view showing the joint of the braces 17;

Fig. 5 is a face view of the sections of the wardrobe folded up.

35 Referring to these drawings, it will be seen that my wardrobe structure includes a sectional top board 10 which may have a length of 5', for instance, and any suitable depth, and depending from this top board

40 are hangers 11, these hangers being hinged to the top board by hinges 12 and being perforated for the passage of a supporting rod 13, the extremity of which is screw-threaded and carries nuts. This rod passes through

45 the hangers 11 and then the nuts are attached to hold the rod thereto. Attached to the under face of the top board 10 adjacent the front edge thereof is a longitudinally extending wire or rod 14, which is

50 preferably attached to the board 10 at its ends and at its middle, though not necessarily so. This wire or rod 14 is for the support of front curtains. The top board is supported by two pairs of legs, there being 55 a pair of legs adjacent each end of the top board. The legs 15 of each pair are pivoted

to each other adjacent the middles of the legs by means of a pivot bolt 16. At their lower ends, each pair of legs is provided with the sectional brace 17 which is formed 60 in two sections pivoted at its ends to the legs and the sections being pivoted at their adjacent ends. These sections are made like the braces of a ladder so that they cannot move downward beyond a position in alignment with each other, but can break upward. These braces act to hold the legs in crossed relation.

65 The lower ends of the rear legs are connected by crossed sectional braces of strap iron. Each of these braces is formed of two sections 18 and 19, the section 18 being relatively long and the section 19 relatively short, the section 18 being pivoted at one end to one of the legs of the rear pair and the section 19 pivoted to the other leg, and these two sections are pivoted to each other and connected by the same joint as is the sectional brace 17 so that the braces can break upward or fold upward but cannot 70 move downward out of substantial alignment. The sections 18 are pivoted to each other at their intersection 20. This construction permits the pairs of legs to be folded into alignment and then one pair of legs 75 on one side of the article shifted toward and into parallel relation to the pair of legs on the other side, as in Fig. 5. These legs at their upper ends, as illustrated in Fig. 2, are joined by a transversely extending hook 90

24 which is pivoted to one of the legs 15 and engages over a stud 25 on the other leg. These members 24 extend inward of the brackets or supporting members 11 so that thereby the top board is held from longitudinal movement relative to the legs. Preferably the top 10 is made in three sections *a*, *b* and *c* hinged to each other so that the sections *b* and *c*, which are relatively 95 narrow, may be turned back upon the top 100 so as to reduce the width of the top for packing purposes, as illustrated in Fig. 5.

105 In order to inclose the collapsible frame of the wardrobe, I engage with the top a piece of fabric 21 which extends over the top, as at 23, and down around the side and end edges of the board so as to completely 110 cover the top board and hang down at the rear of the wardrobe and at the ends thereof. The front of the wardrobe is closed by a curtain 22 which is provided with rings sliding on the rod 14.

By this means a very light and portable wardrobe is constructed which may be readily shifted from place to place, and which may be readily taken apart and packed or stored. In practice inverted hooks will be also carried by the under face of the board 10 upon which articles may be hung. Ordinary clothes hangers are to be disposed upon the rod 15. A practical size for this device 15 is, height 5' 8", length 5', depth 20", and the hanger rod 13 will have a length of 4' 3". When the wardrobe is folded, it will occupy a space of 5' 8" in length, 6" in width, and about 4" in depth. The whole 15 structure weighs about 25 pounds.

I claim:—

1. A foldable wardrobe structure including a top board, members depending therefrom and hinged thereto, a longitudinally 20 extending rod supported by said members but detachable therefrom, two pairs of normally crossed legs detachably engaged with the ends of the top board on its under side, the legs of each pair being pivoted to each 25 other intermediate their ends, foldable braces connecting one pair of legs to the other pair of legs, and foldable braces connecting the legs of each pair and holding them spread apart.

30 2. A foldable wardrobe of the character described including a top board, two pairs of legs, the legs of each pair being pivotally connected to each other intermediate their ends and normally extending across 35 each other in diagonal relation, the upper ends of said legs being adapted to be detachably connected to the under side of the top member, a sectional brace connecting the lower ends of each pair of legs, sectional 40 braces connecting one of the legs of one pair to the corresponding leg of the other pair, said sectional braces crossing each other and being pivoted to each other and being formed of pivoted sections, members 45 hinged to the under side of the top board and normally depending therefrom, a rod normally connecting said members, and a curtain supporting rod connected to the under 50 face of the top board and extending parallel and adjacent to its forward edge.

3. A foldable wardrobe of the character described including a top board, two pairs of legs, the legs of each pair being pivotally connected to each other intermediate 55 their ends and normally extending across each other in diagonal relation, the upper ends of said legs being adapted to be detachably connected to the under side of the top member, a sectional brace connecting 60 the lower ends of each pair of legs, sectional braces connecting one of the legs of one

pair to the corresponding leg of the other pair, said sectional braces crossing each other and being pivoted to each other and being formed of pivoted sections, members 65 hinged to the under side of the top board and normally depending therefrom, a rod normally connecting said members, a curtain supporting rod connected to the under face of the top board and extending parallel 70 and adjacent to its forward edge, and a drapery attached to the top board and extending around the sides thereof and across the front thereof and having its upper edge connected by rings to the curtain supporting 75 rod.

4. A foldable wardrobe of the character described including a top board formed of longitudinally extending sections hinged to each other, the middle section having at its 80 opposite ends hinged brackets, a hanger supporting rod detachably engageable with said brackets, two pairs of legs, the legs of each pair being pivotally connected to each other intermediate their ends and normally crossing each other in diagonal relation, foldable braces engaging the lower ends of each pair of legs and holding the legs in crossed relation, foldable braces engaging the rear legs of each pair of legs with each other, a 85 member connecting the upper ends of each pair of legs, said member extending transversely beneath the ends of the top board and engaging against the faces of said brackets to thereby hold the legs and top 90 board in alinement, fabric engaged with the top board and extending over the back and around the ends of the frame inclosing the wardrobe, and curtains slidably engaged with the top board adjacent its forward 95 edge.

5. A foldable wardrobe of the character described including a top board, members depending from the ends thereof, longitudinally extending rods supported by said 100 members, two pairs of legs, the legs of each pair being pivotally connected to each other intermediate their ends and normally crossing each other in diagonal relation, foldable 105 braces engaging the lower ends of each pair of legs and holding the legs in crossed relation, foldable braces engaging the rear legs of each pair with each other, and a member connecting the upper ends of each pair of legs and extending transversely beneath 110 the ends of the top board and engaging against the faces of said first named members to thereby hold the legs of the top board in alinement.

In testimony whereof I hereunto affix my 115 signature.

MARY R. KEEGAN.
